(57) **CLAIM**

The ornamental design for a three-way clamp body, as shown and described.

DESCRIPTION

A body of a three-way clamp such as used as part of a holder for an oral suction device such as that disclosed by Homra, U.S.Pat. No. 6,077,074, issued Jun. 20, 2000.

FIG. 1 is a perspective view of a three-way clamp body, as taken generally from the top front.

FIG. 2 is a perspective view of the three-way clamp body of FIG. 1, but as taken generally from the bottom rear.

FIG. 3 is a top plan view of the three-way clamp body of FIG. 1.

FIG. 4 is a left side elevational view of the three-way clamp body of FIG. 1.

FIG. 5 is a bottom plan view of the three-way clamp body of FIG. 1.

FIG. 6 is a right side elevational view of the three-way clamp body of FIG. 1.

FIG. 7 is a front elevational view of the three-way clamp body of FIG. 1.

FIG. 8 is a rear elevational view of the three-way clamp body of FIG. 1; and,

FIG. 9 is a sectional view as taken on line 9—9 of FIG. 8.
